METALLURGICAL APPARATUS

Carl J. Westling, West Orange, N. J., assignor to
 Minerals and Metals Corporation, New York,
 N. Y., a corporation of Delaware

Application June 4, 1942, Serial No. 445,721

8 Claims. (Cl. 259—4)

This invention relates to the beneficiation of finely divided metallic compounds or ores by reduction, roasting, or other metallurgical processes, and relates particularly to improvements in the apparatuses disclosed in my copending application Serial No. 422,930, filed December 15, 1941, and to improvements in multiple circular hearth furnaces.

Furnaces or roasters of the multiple hearth type are well known in the art. These furnaces include a number of circular arch refractory hearths built one above another in a suitable furnace shaft. Ore is fed to the top hearth and is then rabbed toward the center where it drops to the hearth below, then rabbed toward the outer periphery of the hearth where it drops again to the next lower hearth, and so on down through the furnace.

The rabbling is accomplished by means of a plurality of arms provided with inclined plow blades which are mounted upon a common hollow central shaft that is rotated in any suitable way to advance the ore through the furnace shaft as described above.

Reduction of the ore is accomplished in furnaces of this type by the flow of a reducing gas countercurrent to the direction of movement of the ore. The gases and furnaces of this type act on the charge by flowing over it on the hearths and by flowing through the charge as it drops from one hearth to the next lower hearth. The reaction of the gas with the charge in this type of furnace is relatively quite slow, especially when the object of the treatment is to reduce an ore to metal. The reason for this is that the major portion of the gases bypass the material and do not come in close contact with the material undergoing reduction. Moreover, the heat for reduction usually is obtained by burning the gas at the different hearths with the result that the products of combustion mix with the reducing gases and diminish the reducing action thereof.

Another difficulty encountered when using this type of furnace for reducing ores is that, as the ore is changed gradually to a metallic state, it has a tendency to sinter and stick to the hearths and rabbles at the zones where there are concentrations of heat sufficient to soften the metallized particles.

It is customary to cool the shafts and the rabble arms of such furnaces by passing air through the arms and the hollow shaft. This cooling operation has the disadvantage that it removes a large amount of the heat from the furnace and moreover may be a source of potential danger in

asmuch as in operations in which the reducing agent used contains a substantial percentage of hydrogen, leakage of air from the shaft may constitute a serious explosion hazard.

An object of the present invention is to overcome the disadvantages of such multiple circular hearth furnaces as those described above and to provide an apparatus for more efficiently reducing, roasting or otherwise treating ores or metallic compounds.

Another object of the invention is to combine the advantages of an efficient reducing furnace, such as that described in application Serial No. 422,930 with the multiple circular hearth type of furnace to obtain a more efficient heat interchange between the gases coming up through the bottom of the furnace and the charge and to utilize gases for the pretreatment of the charge.

Another object of the invention is to overcome the danger of explosions in such furnaces and to provide a more efficient cooling of the rotating shaft and the stirring or rabbling arms of such a multiple circular hearth furnace and at the same time to make use of the heat so absorbed from the mechanism to dry and heat the freshly introduced ore.

In general, furnaces and roasters of the type embodying the present invention resemble the multiple circular hearth furnaces described above, in that they include the usual circular, refractory hearths, the rabbling arms or stirrers and the central hollow shaft supporting such arms for rotation. In these older furnaces the flow of material is radial alternately in or out from the center to the outside and vice versa. My device differs from prior devices, however, by the provision of a reducing hearth at the bottom of the shaft including a plurality of circular troughs through which the charge is caused to flow circumferentially, by directing reducing gases upwardly through the bottom of the troughs, thereby causing a state of fluidity in the charge and assuring intimate contact between the gases and the charge. The partially spent reducing gases then flow countercurrent to the charge on the hearths to preheat and drive off the moisture in the charge. Also, inasmuch as the reducing gases contain a certain amount of reducing agents, a partial reduction of the ore is obtained as the ore is brought up to the desired temperature.

In the event that the ore used requires roasting to drive off sulfur or carbon dioxide, this action may also be accomplished in my furnace by isolating the gases in the roasting section from

the gases in other hearths of the furnace. With an ore of this type, a further advantage is gained by conserving the heat in the ore from the roasting operation since it passes immediately down to the reducing hearths without cooling or re-handling.

In furnaces of the type embodying the present invention the central shaft for supporting the rabbling arms may be cooled by means of washed spent reducing gases, thereby minimizing the danger of explosions in the shaft. The furnace is so arranged that when the cooling gases reach the level of the top hearth, they are discharged over it from the shaft and arms and thence pass into an additional top deck in the furnace in the form of a heat exchanger through which the gases may flow to give up their heat to the raw ore fed to the top of this deck, thereby drying it and placing it in condition for further treatment. This gas, inasmuch as it is isolated from the other reducing gases, preferably by means of gas lock, may then be sent through a washer, cooled and recirculated through the shaft to cool the shaft and to dry additional quantities of ore. The use of recycled gas for cooling purposes holds the heat loss at a minimum by transferring to the cold ore the maximum amount of sensible heat picked up in the shaft and rabbling arms.

For a better understanding of the present invention, reference may be had to the accompanying drawings, in which:

Fig. 1 is a view in vertical section of a typical form of a furnace or roaster embodying the present invention;

Fig. 2 is a view in section taken on line 2—2 of Fig. 1;

Fig. 3 is a view in section taken on line 3—3 of Fig. 1;

Fig. 4 is a view in section taken on line 4—4 of Fig. 1;

Fig. 5 is a view in section taken on line 5—5 of Fig. 1, and

Fig. 6 is a view in section taken on line 6—6 of Fig. 1.

The form of the invention chosen for purposes of illustration may consist of a cylindrical refractory furnace shaft 10, which is mounted on suitable standards 11 and is provided with a plurality of substantially circular refractory hearths 12 and 13. Each of these hearths is accessible from the exterior of the furnace shaft, by means of cleanout or observation doors 14 of the conventional type. While only four refractory hearths are illustrated, it will be understood that the furnace may be provided with more or fewer hearths, as desired.

Above the uppermost refractory hearth 13 is deck 15, which may be formed of two spaced apart annular steel plates 15a and 15b forming a heat exchanger for heating and drying ore received on the deck plate 15a. As shown in Fig. 2, the space between the plates 15a and 15b may be formed into a spiral gas passageway 16 by means of the outer casing of the furnace and a spirally arranged plate 16a. The inner end of this passageway communicates through an opening 16c with the space in the furnace shaft between the upper refractory hearth 13 and the deck 15. The passageway 16 is provided with an outlet 17 opening to the exterior of the furnace for a purpose which will be described herein-after.

The bottom of the furnace shaft 10 is closed by means of a refractory hearth 18 which is pro-

vided in its upper surface with a pair of generally V-shaped, annular troughs 19 and 20. As shown in Fig. 3, an inclined passage 21 of generally V-shaped cross-section connects the troughs 19 and 20 so that the charge which is received in the trough 19 may be transferred outwardly to the trough 20.

Partially reduced and/or preheated ore is advanced around these troughs by means of a gaseous current in a manner similar to that disclosed in application Serial No. 422,930 referred to above. As described in application Serial No. 422,930, the gas passing upwardly through the body of ore acts to suspend the ore and impart to it a fluidity similar to water. The flow of the finely divided ore is accomplished by maintaining a greater depth of ore at the feed end of the hearth than at the discharge end, thereby causing the ore to flow like water under a pressure head. The bottom ends of the troughs at the apex thereof are provided with circumferential slots 19a and 20a which communicate with gas supply manifolds 22 and 23, respectively.

As best shown in Fig. 4, the manifold 23 is of annular formation and includes a laterally extending port 23a through which the heated reducing gas is delivered into the channel 23 from an exterior source, not shown.

The manifold 22 is of semi-circular shape, concentric with the manifold 23 and is provided with an inlet port 22a for the heated reducing gas. The hearth 18 is further provided with a plurality of radially extending passages 24 communicating with the passage 22 and radially extending passages 25 communicating with the manifold 23. These passages communicate, in turn, with upwardly extending passages 26 and 27, through which the reducing gas is delivered into the bottom slots 19a and 20a of the troughs 19 and 20. As shown, particularly in Figs. 5 and 6, the slots 19a and 20a are not entirely open but reinforced at intervals with vertically extending refractory members 28 having generally pyramidal top portions 28a terminating at the bottoms of the troughs 19 and 20. These members 28 contain ducts 29 horizontally communicating with the passages 26 or 27 to deliver the gases into the slots 19a and 20a of the troughs 19 and 20. As shown in Figs. 1 and 5, the ducts 28b in the members 28 may be provided with manually adjustable slide valves 29a which are adjustable from the exterior of the shaft to control the rate of flow of gas upwardly through the troughs and thereby control the reduction rate and the rate of flow of the charge.

The provision of two separate manifolds 22 and 23 permits a washed recycled gas to be introduced into the inner trough 19 and fresh reducing gas to be introduced into the trough 20. As a result, a marked reduction in the volume of the fresh reducing gas can be made and a more economical treatment of the ore results.

In order to prevent sticking of the ore in the troughs 19 and 20 and to assure a loose formation of the particles of the charge so that free passage of the gas therethrough and intimate contact between the reducing gases and the charge are obtained, stirrers may be provided. As illustrated in Fig. 1, the stirrers 30 may be of generally triangular outline and formed of a vertically extending rod 30a having a plurality of cross pieces 30b thereon. These stirrers 30 are mounted on arms 31, which are, in turn, supported on a hollow cylindrical shaft 32 that is rotatably mounted concentrically with the fur-

nace shaft. As illustrated in Fig. 1, the shaft 32 may be supported at its lower end by means of a bearing 33 and is driven by means of a suitable reduction gearing 34 from a source of power, not shown. Suitable seals or gas locks 36 between the shaft 16 and the hollow shaft 32 may be provided for preventing leakage of the gases.

The shaft 32 extends upwardly throughout the entire height of the furnace shaft and is provided with rabbling arms 38 for stirring and advancing the ore over the circular hearths 12 and 13 and the deck 15. The rabble blades 39 on the arms 38 are so inclined that the ore which is fed into the hopper 40 at the top of the furnace shaft and onto the shelf 41 therein, is fed inwardly along the deck 15 to the aperture 42 adjacent the shaft 32 through which it falls to the shelf 43 above the next adjacent hearth 13, is moved outwardly by the blades 39 to the periphery of the hearth to fall onto the next adjacent hearth, finally falling to the hearth 13 adjacent its center zone. The stirring blades 39 on the arms 31 then move the charge slowly outwardly into the trough 19, and create a pressure head on the ore by producing a greater depth of ore in the trough 19. The ore suspended in a state resembling fluidity by the gases flows around the trough 19 toward the transverse or inclined trough 21, shown in Fig. 3. The charge is then transferred through the trough 21 by means of the flow of the gases and the pressure head into the trough 20 where it is advanced by and subjected to further action of the treating gases as it passes around this trough to the discharge opening 46.

Control of the flow of the charge through the troughs 19 and 20 may be obtained by varying the supply of gas delivered to various portions of the troughs by means of the valves 29a. Thus, if the gas is shut off from any one section of the trough 19, the charge at this zone will be quiescent and will form a dam preventing the flow of the charge beyond this dam. Nevertheless, the stirrers 30 can pass through the quiescent portion of the charge without advancing it appreciably. Advantage may be taken of this flow or lack of flow to direct the transfer of ore from one trough 19 to the other trough 20 and also to control the circumferential flow in the troughs so that it will be continuous in one direction toward the reduced product exit port.

Additional heat for a reducing operation can be obtained, if desired, by burning some of the reducing gases at various zones above the hearths. Thus, effective control of the heating conditions within the furnace can be obtained. The partially or completely spent reducing gases may be drawn off through the gas outlet 47 between the hearths 12 and 13 so that these gases do not affect the ore on the deck 15 or the hearth 13.

In order to effect cooling of the shaft 32 and arms 31 and 38 and drying of the ore on the deck 15, washed spent reducing gases may be introduced into the shaft 32 through the manifold 48 at the lower end of the shaft 32. The gas travels upwardly through the shaft 32 and arms 31 and 38 absorbing heat therefrom. This heated gas may then be discharged through the port 32a between the hearth 13 and the deck 15 and then passes through the gas port 16c into the spiral passage 18, dissipating its heat through the steel plates 15a and 15b and drying the ore traversing the deck 15. The gas may then be withdrawn through the outlet port 17, reashed and recycled through the shaft 32 for another cooling and dry-

ing operation. The advantage of keeping this shaft cooling gas separate from the spent reducing gases passing out of the outlet 47 is that this cooling gas will not pick up as much dust since this gas purposely will not contain enough heat to dry the ore to a dusty state and this gas therefore does not require extensive cleaning before being recycled.

From the preceding description of a typical form of apparatus embodying the present invention, it will be clear that I have provided an efficient apparatus for reducing or otherwise treating ores or other materials at relatively low temperature and in which high efficiency is obtained, because of the intimate contact of the gases with the material being treated. Moreover, there is less waste of gas and of the heat of the gas because of the efficient heat interchange in the various stages of the apparatus. The multiple rabble hearth section of the furnace is used primarily as an efficient heat exchanger between the down-flowing ore and the hot gases coming up from the trough-type reducing section at the bottom. However, some reduction will take place on the upper hearths if the conditions are favorable toward such reduction. The extent of reduction is, of course, dependent upon temperature conditions, the equilibrium between the oxide and the gases and the time required for the oxide to traverse the upper sections of the furnace. The time is further dependent upon the rate at which the reduction of the ore can be completed in the troughs 19 and 20.

It will be understood that the device is susceptible to considerable modification in its details of construction and that the number and size of the hearths, the number and size of annular reducing troughs, the details of the rabbles, and the like, may be changed as the purpose demands without departing from the invention. Therefore, the form of the invention disclosed herein should be considered as illustrative and not as limiting the scope of the following claims.

I claim:

1. An apparatus for treating a finely divided solid material with a gas comprising a furnace shaft, a substantially circular hearth therein having at least one curved trough therein extending around the hearth for receiving said material and having a perforate bottom, and means for supplying gas under pressure through the perforate bottom of said trough to render said material fluent so that it flows along said trough and to bring said gas into intimate contact with said material.

2. An apparatus for treating a finely divided solid material with a gas comprising a furnace shaft, a substantially circular hearth therein having a plurality of substantially annular troughs therein for receiving said material, means for supplying gas under pressure through the bottom of said troughs to render said material fluent so that it flows along said troughs and to bring said gas into intimate contact with said material, and at least one passageway connecting said troughs for transferring said material from one trough to another.

3. An apparatus for treating a finely divided material with gases, comprising a furnace shaft, at least one substantially circular hearth therein having a plurality of downwardly tapering open-bottom annular troughs therein, means for introducing a gas through the bottoms of said troughs to buoy the material upwardly so that the mate-

rial flows around the troughs, and at least one downwardly tapered open-bottom trough communicating with the adjacent first-mentioned troughs for transferring the material from one of said first-mentioned troughs to another.

4. An apparatus for treating a finely divided solid material with a gas, comprising a furnace shaft, at least one substantially circular hearth in said shaft, having a plurality of annular troughs concentric therewith and each having a perforate bottom, means for feeding said material to substantially the center zone of said hearth, means for advancing said material outwardly into the innermost trough, means for directing a gas upwardly through the perforate bottoms of said troughs to render the material fluent so that it flows around said troughs, and means for transferring said material from the innermost trough outwardly into the next adjacent trough.

5. An apparatus for treating a finely divided solid material with a gas, comprising a furnace shaft, at least one substantially circular hearth in said shaft, having a plurality of annular troughs concentric therewith and each having a perforate bottom, means for feeding said material to substantially the center zone of said hearth, means for advancing said material outwardly into the innermost trough, means for directing a gas upwardly through the perforate bottoms of said troughs to render the material fluent so that it advances around said troughs, means for transferring said material from the innermost trough outwardly into the next adjacent trough, and means rotatable about an axis concentric with said troughs for agitating the material therein.

6. An apparatus for treating a finely divided solid material with a gas comprising a furnace shaft, a substantially circular hearth therein having at least one substantially annular trough therein for receiving said material and having a perforate bottom, means for supplying gas under pressure through the perforate bottom of said

trough to render said material fluent so that it flows along the trough and to bring said gas into intimate contact with said material, and means for selectively controlling the flow of gas into different portions of said trough to control the rate at which the material can advance along said trough.

7. In a furnace, the combination of a furnace shaft, a plurality of vertically spaced substantially circular hearths in said shaft, having apertures therein for passage of material downwardly from one hearth to another, means for advancing said material along said hearths toward said openings, another hearth in the bottom of said shaft having at least one substantially annular trough therein for receiving material delivered from the hearths next above, said trough being substantially V-shaped in cross-section and having a slot at its bottom, and means for delivering a heated gas through said slot to render said material fluent so that it flows along said trough, said gas thereafter flowing upwardly through said furnace shaft countercurrent to the movement of said material.

8. In a furnace, the combination of a furnace shaft, a plurality of vertically spaced substantially circular hearths in said shaft, having apertures therein for passage of material downwardly from one hearth to another, means for advancing said material along said hearths toward said openings, another hearth in the bottom of said shaft having a plurality of substantially annular troughs therein for receiving said material, said troughs being substantially V-shaped in cross-section and having narrow annular slots at their bottoms, an inclined V-shaped trough having a slot in its bottom connecting adjacent annular troughs, and means for delivering a heated gas through said slot to render said material fluent so that it flows along said trough, said gas thereafter flowing upwardly through said furnace shaft countercurrent to the movement of said material.

CARL J. WESTLING.
